ARM CHAIR

Miguel Rodrigo, Republica de Chile Street 284,
Lima, Peru

Filed Oct. 23, 1965, Ser. No. 87,884

Term of patent 14 years

(Cl. D15—1)

FIG. 1

FIG. 2

FIG. 3

The essential features of my design reside in those portions shown in full lines on the drawing.

I claim:

The ornamental design for an armchair, as shown and described.
